UNITED STATES PATENT OFFICE.

MELVIN COLBY, OF MOUNT HOORB, WISCONSIN.

DIRECTION-INDICATOR.

1,233,189.

Specification of Letters Patent. Patented July 10, 1917.

Application filed March 24, 1916. Serial No. 86,523.

To all whom it may concern:

Be it known that I, MELVIN COLBY, a citizen of the United States, residing at Mt. Horeb, in the county of Dane and State of Wisconsin, have invented certain new and useful Improvements in Direction-Indicators; and I do hereby declare the following to be a full, clear, and exact description of the invention, such as will enable others skilled in the art to which it appertains to make and use the same.

This invention relates to improvements in a direction indicator for automobiles, and has for its primary object to provide a device, whereby an operator of the automobile may notify the traffic in the front and rear thereof, his intended turn of travel, by securing one of the devices to the front and rear of the automobile.

Another object of this invention is to provide a frame, having a casing secured thereto, which is provided with an opening to display direction indicating symbols when brought in registration therewith, to notify the traffic the direction which the automobile is going to turn, either to the left or right.

A further object of this invention is to provide a pair of arms journaled on a transverse shaft, having plates or disks secured to their free ends which bear the symbols R and L, either one of which are adapted to swing in view of the traffic through the opening in the casing.

A further object of this invention is to provide a pair of solenoids operatively connected to the arms for raising the arms upwardly to bring the direction symbols in view through the opening in the casing, upon energizing the solenoids, which may be in circuit with the lighting system now employed upon automobiles.

A further object of this invention is to provide a novel means of locking the arms in a raised position, and which is capable of releasing the arms to allow them to return to their normal position upon energizing a pair of magnets.

A still further object of this invention is the provision of a direction indicator of the above stated character, which shall be simple, durable and efficient, and which may be manufactured and sold at a comparatively low cost.

With these and other objects in view as will become more apparent as the description proceeds, the invention consists in cer-

tain novel features of construction, combination and arrangement of parts as will be hereinafter more fully described and claimed.

For a complete understanding of my invention, reference is to be had to the following description and accompanying drawings, in which:

Fig. 1 is a front elevation of a direction indicator, constructed in accordance with my invention,

Fig. 2 is a plan view with the casing and magnets removed,

Fig. 3 is a vertical sectional view, illustrating one of the arms locked in a raised position,

Fig. 4 is a fragmentary transverse sectional view, taken on the line 4-4 of Fig. 3, looking in the direction indicated by the arrows.

Fig. 5 is a fragmentary sectional view, illustrating the connection between the solenoids and the arms, and

Fig. 6 is a diagrammatical view of the wiring diagram.

Referring in detail to the drawings, the numeral 1 indicates a frame, having a bottom 2 secured thereto and a casing 3 which is provided with an opening 4, that is closed by a piece of glass 5. A transverse shaft 6 is secured to the sides of the frame 1 and adjacent one end thereof, and has journaled thereon collars 7 and 8 to which are secured arms 9 and 10 respectively. The arm 10 is bent as illustrated at 11 to allow the free end to extend in parallel alignment with the arm 9 and in close relation thereto. Secured to the free ends of the arms 9 and 10 are circular disks or plates 12 and 13 and the disk 12 has the symbol R painted thereon or applied in any suitable manner, standing for the word "right." The disk 13 is provided with a symbol L, which stands for the word "left." Either of the disks 12 or 13 are adapted to be swung upwardly in rear of the opening 4 to display the direction symbols R or L by an electrical means, which will be hereinafter more fully described.

A transverse rod 14 is secured to the sides of the frame 1 intermediate the ends thereof and has secured thereon brackets 15 and 16 to which are secured solenoids 17 and 18, having cores 19 and 20. The cores 19 and 20 are each provided with one of their ends bifurcated to receive the ends of connecting links 21 and 22 which are secured at their other ends to the collars 7 and 8. The sole-

noids 17 and 18 are in circuit with the lighting system of the automobile (not shown) and are each controlled by a push button. Upon energizing the solenoid 17, the core 19 will be drawn within the solenoid 17 and cause the arm 9 to swing upwardly and display the direction indicating symbol R through the opening 4 of the casing 3. To display the direction indicating symbol L, the solenoid 18 is energized and the arm 10 will swing upwardly upon the transverse shaft 6.

In order to lock either of the arms 9 or 10 in a raised position, a downwardly inclined block 23 is secured to one side of the frame 1 adjacent the transverse rod 14 and has secured thereon a bracket 24, which supports a pair of magnets 25. Secured to the block 23 is a spring pressed armature plate 26 which overlies the end of the magnet and has secured thereto an arm 27. The arm 27 is offset as illustrated at 28 and twisted to provide a locking plate 29, which is notched to form a shoulder 30, which will engage either of the arms 9 or 10 and lock them in a raised position, thus continuously displaying either of the direction indicating symbols R or L. The magnets 25 are in circuit with the lighting system of the automobile and are controlled by a push button, whereby the circuit to the magnets 25 may be closed or completed upon pressing the push button and the spring pressed armature plate 26 will be energized and release either of the arms 9 or 10 and allow them to return to their normal position by gravity.

Referring to the wiring diagram as illustrated in Fig. 6, it consists of a storage battery 31, which may be the storage battery employed on automobiles for furnishing current for the lighting system. A conductor 32 is connected to the storage battery and has connected thereto, a conductor 33 which connects with the solenoid 17. A conductor 34 is connected to the solenoid 17 and to a push button 35 arranged in convenient reach of the operator of the automobile. A return conductor 36 is connected to the push button 35 and to the storage battery 31, whereby upon closing the circuit through the push button 35, the solenoid will be energized and cause the arm 9 to swing upwardly and display the direction indicating symbol R. A conductor 37 is connected to the conductor 32 and to the solenoid 18. A conductor 38 is connected to the solenoid 18 and to the push button 39, arranged adjacent the push button 35. A conductor 40 connects the push button 39 with the return conductor 36 and upon closing the circuit

through the push button 39, the solenoid 18 will be energized and cause the arm 10 to swing upwardly and display the direction indicating symbol L. The conductor 32 is connected to the magnets 25 and said magnets are connected to a push button 41 arranged between the push buttons 35 and 39, by a conductor 42. A conductor 43 connects the push button 41 with the return conductor 36 and by closing the circuit through the push button 41, the magnets 25 will be energized and attract the spring pressed armature 26, causing the locking plate 29 to move and release the arm 9 or 10, whichever may be locked in a raised position.

An electric lamp socket is secured to the casing 3 adjacent the opening 4 and has secured therein an electric lamp for illuminating the direction indicating symbols at night. The electric lamp receives electricity from the lighting system of the automobile.

While I have shown and described the preferred embodiment of my invention, it will be understood that minor changes in the construction, combination and arrangement of parts may be made without departing from the spirit and scope of the invention as claimed.

Having thus described my invention, what I claim is:—

A direction indicator comprising a frame, a casing secured to the frame and having an opening, a transverse shaft journaled in said frame below said opening, horizontally disposed solenoids pivoted to the frame at one end thereof and at a point below and laterally of said shaft, arms pivoted to the shaft and normally extending horizontally in the frame, direction indicating symbols carried by the arms, cranks secured to the arms and to the cores of the solenoids, means for energizing the solenoids to swing the arms upwardly in the casing and bring the direction indicating symbols in view through the opening; a block secured to the frame, magnets carried by the block, a resilient arm secured to the block and overlying the magnets, a catch formed on said arm and extending upwardly within the casing to engage the first mentioned arms when swung upwardly within the casing, and means for energizing the magnets to free the catch from the first mentioned arms to permit said arms to return to a horizontal position.

In testimony whereof I affix my signature in presence of two witnesses.

MELVIN COLBY
